(57) **CLAIM**

The ornamental design for a drain basket retainable on sink, as shown and described.

DESCRIPTION

FIG. 1 is a perspective view of the top, front and right side of a drain basket retainable on sink showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a reduced top plan view thereof shown in place on a sink with the retractable support rod in an extended position.

The elements shown in broken lines are for illustrative purposes only and do not form any part of the claimed design.
